UNITED STATES PATENT OFFICE.

JOHN W. PEARSON, OF CHICAGO, ILLINOIS.

ARMATURE.

1,320,795.

Specification of Letters Patent.

Patented Nov. 4, 1919.

Application filed August 7, 1916. Serial No. 113,614.

To all whom it may concern:

Be it known that I, JOHN W. PEARSON, a citizen of the United States of America, and a resident of Chicago, county of Cook, and State of Illinois, have invented certain new and useful Improvements in Armatures, of which the following is a specification.

This invention relates to dynamo-electric machinery, and more particularly to the arrangement and insulation of the windings on the armature.

The main objects of this invention are to provide an improved form of direct current armature adapted for use in a small motor

15 which must receive its power directly from a high voltage source, such for instance, as used in direct current railway service, where the voltage ranges from five hundred to seven hundred volts, and where as a factor
20 of safety 300 volts is added to the maximum operating voltage, making a test condition of 1000 volts direct current; to provide an improved form and arrangement of armature insulation and means for holding the
25 several coils in place respectively; and to so arrange and insulate the coils of a drum winding on a slot wound armature as to permit of operating the machine on high voltage without danger of rupturing the insulation or shorting coils.
30

An illustrative embodiment of this invention is shown in the accompanying drawings, in which—

Figure 1 is a side view of the armature.

35 Fig. 2 is an end view from the right of Fig. 1.

Fig. 3 is an end view from the left of Fig. 1.

Fig. 4 is an axial section on the line 40 A—A of Fig. 1, the windings being omitted, except a fragment on one side.

Fig. 5 is a cross section on the line B—B of Fig. 1, the windings being omitted.

Fig. 6 is an enlarged fragmentary section 45 across one of the slots of the finished armature.

Fig. 7 is a simplified or elementary diagram of the armature winding, an equal number of slots and commutator segments being shown and each coil being represented by a single turn or loop.

In the construction shown in the drawings, the laminated drum or core 1 consists of soft iron plates 2 held together on the shaft 3 in a manner usual for small armatures. Preferably the laminæ 2, and also

the insulating end plates 4 at the ends fit tightly on the shaft, so as to be secured sufficiently by friction. The adjacent parts of the shaft are covered with insulation 5, 60 such as tape or the like, which further holds the plates 4 in place. Said core 1 is provided with transverse slots 6 preferably disposed at a slight angle, or somewhat spirally, as usual in armatures, said slots being 65 produced by providing suitable notches in the plates 2 and 4 when they are punched from sheet stock, and then duly alining same on the shaft 3 when assembled, as will be understood. 70

Each slot 6 is relatively deep and narrow and has a restricted opening or mouth 7 having thin overhanging flanges or lips 8. The corresponding intermediate teeth 9 are also relatively tall and narrow and are T-shaped. When the armature is finished, each slot contains overlying parts of two separate coils or "bundles" 10, disposed widely apart electrically, preferably nearly one hundred and eighty electrical degrees, one coil being disposed in the bottom of the slot and the other adjacent to the mouth, said coils being thoroughly insulated from each other and from the core 1.

The insulating means provided in each slot includes a slot lining member 11 of U-shape (see Figs. 5 and 6), against which the inner or bottom coil is disposed, and an inner member 12 having its edges turned convergently in a more nearly tubular or cylindrical shape, wherein the outer or top coil is housed. The edges of the insulator 12 are held in place by the slot closure plate or key 14, which is driven lengthwise into place under the lips 8 after the coils are in place. The parts all fit tightly together, and the key 14 is secured by friction. The insulators 11 and 12 are somewhat flexible and consist of strips of high grade insulating material, known as "horn fiber", which in appearance resembles heavy paper. Said insulators extend from end to end of the slots 6, including the end insulators 4, so that the coils are thoroughly insulated from the core. The key 14 may consist of fiber-board or suitable wood may be used.

The number of slots may be varied according to the size of armature required, nineteen being provided in the present embodiment, said slots being numbered in order from 1 to 19 (see Fig. 7). 110

The armature is slot wound and the coils

10 are arranged on the drum-like core in the form of a drum winding, which is applied as follows: First, the insulators 11 being in place, eight coils are disposed in direct regular order in certain slots, Nos. 1 to 8 and 5 9 to 16 for the opposite sides respectively (see Figs. 6 and 7). Then a layer of suitable insulation 16, preferably silk tape, is applied or wound in like manner directly 10 over said coils. Part of the insulators 12 are next inserted, over the coils already in place. A second group of eight coils is then applied, being disposed in a similar manner successive to and in series with the first coils, 15 but in slots 9 to 16 and 17 to 5 for opposite sides respectively, and partly overlying the first group of coils. A layer of insulation 16 is then applied over the second group of coils. Then the rest of the insulators 12 are 20 inserted. Finally, a third group of three coils is applied in like manner in certain slots, 17 to 19 and 6 to 8 for opposite sides, and a layer of insulation 16 is applied thereto. A final outer protective layer of 25 tape may well be added over all. The heads of the armature being thus protected with silk tape present a smooth rounded surface,—hence the term "bald head" which is the shop term applied to these armatures.

30 The armature may be machine wound to advantage, as by means of a suitable chuck and appliances understood by those skilled in the art, the windings being continuous and commutation loops 17 being formed at 35 the commutator end of the slots, said loops preferably being provided with protective sleeves 18 of suitable woven fabric leading from the slots 6 to the corresponding segments 19 of the commutator 20 (see Figs. 1, 40 2 and 4).

On account of physical limitations, and commercial efficiency in manufacture, the number of slots on a given armature is usually less than would be preferred from a 45 commutation point of view. Hence, in order to minimize sparking, the commutator is preferably provided with more segments than there are armature slots, the number of segments being some multiple of the number of slots. In the drawings (except Fig. 50 7), there are three times as many segments as slots, or fifty seven segments, and each coil or bundle comprises three equal parts connected in series to three corresponding 55 segments. Hence when any two adjacent segments are connected or bridged by a brush, only one third of a complete coil or bundle is short circuited, instead of a whole coil.

60 As there are three loops 17 leading from each slot, each inclosed in a separate sleeve 18, said sleeves are distinguished in regular order according to a simple code, for instance red, white, and green sleeves being 65 used respectively. Then when the winding

is finished the color code indicates to which segments the several loops are to be soldered respectively in connecting the coils to the commutator.

The insulation provided by the medial 70 layer of tape 16 overlaps itself in an increasing degree approaching the center or shaft 3 which provides a multifold protection against grounding of the armature coils against the frame or bearing bracket of the 75 motor, through the inevitable accumulation of conductive dust and like foreign material. In the embodiment shown it is to be noted that the difference in potential between adjacent coils, inner and outer, is about nine 80 tenths of the entire impressed voltage, so that when the full maximum of 1000 volts is applied to the brushes the insulation between coils must withstand about 900 volts. When the windings and insulation are all 85 in place the armature is thoroughly impregnated with varnish and baked, whereupon it must stand an insulation test of about two thousand volts to the shaft or ground.

One of the more important uses for 90 motors having armatures embodying this invention is for operating accessory devices used in connection with direct current street railway equipment, especially where the motor current is taken directly from the railway 95 power circuit. Certain parts or features of the invention may be used on low voltage high speed (3000 to 4000 R. P. M.) armatures to keep machine wound windings in position against centrifugal force, reduce 100 the windage friction and exclude dirt, which tends to deteriorate the windings. For such work the motor is preferably compound wound, though a simple shunt motor embodying the invention may be used.

105 Although but one specific embodiment of this invention is herein shown and described, it will be understood that numerous details of the construction shown may be altered or omitted without departing from the spirit 110 of this invention as defined by the following claims.

I claim:

1. A drum wound slotted armature adapted for high potential direct current, and having a continuous winding disposed in its slots, said winding being arranged in the form of and comprising a plurality of coils disposed one over another in the slots, with a correspondingly disposed winding of tape 115 insulation between adjacent coils.

2. A slot wound direct current armature having a continuous closed circuit winding including a set of coils the opposite sides of which are disposed in slots nearly 120 one hundred and eighty electrical degrees apart, successive coils being disposed in immediately successive slots respectively, and and a pair of conduit-like insulation members in each slot for housing the adjacent 125 130

parts of two separate coils disposed therein respectively, and tape windings directly overlying the several coils respectively throughout their lengths.

- 5 3. In a slot wound armature a deep narrow slot having a restricted mouth or opening with overhanging lips or flanges, a U-shaped lining of insulation for said slot, a coil having one side disposed in the bottom 10 of said slot, an insulating strip resting on said coil and having its edges turned outward and convergently to form a tubular casing or conduit, a second coil of widely different potential from the first mentioned 15 coil and having one side disposed in said casing and a rigid key fitting tightly between said casing and said lips for securing said coils in place, and complete windings of tape immediately overlying said coils respectively.
- 20 4. A direct current slot wound armature having tape wound over the coils and across the ends and varnished and adapted to hold the coils in place at the ends, said ends of

the armature being rounded and presenting 25 a bald head appearance and being adapted to minimize windage friction, same being adapted and arranged to seal up the head and so prevent grounds.

5. A slot wound armature of the character 30 described, comprising a plurality of coils arranged in the slots and connected in closed circuit, each slot containing one side respectively of each of two separate coils disposed approximately one hundred and eighty electrical degrees apart, and a winding of insulating tape disposed between adjacent coils to prevent electrical short circuiting.

6. The method of winding a bi-polar slotted armature which consists in winding 40 into the slots and across the core ends coils of insulated conductors alternately with correspondingly disposed complete turns of tape insulation.

Signed at Chicago this 24th day of 45 July 1916.

JOHN W. PEARSON.
